CASH REGISTER

Kurt Vogelgesang and Erich Wagner, Berlin, Germany, assignors to The National Cash Register Company, Dayton, Ohio, a corporation of Maryland (incorporated 1926)

Application July 10, 1934, Serial No. 734,537
In Germany July 17, 1933

14 Claims. (Cl. 101—93)

This invention relates to improvements in the printing mechanism for cash registers of the type illustrated and described in Letters Patent of the United States No. 751,611 issued February 9, 1904 to Thomas Carroll, and U. S. Patent No. 1,594,167, issued July 27, 1926 to Frederick L. Fuller.

In cash registers and accounting machines where the same impression mechanism is employed to make records either upon an issuing check or an insertable slip, and where the impression mechanism functions identically in both cases, it is the usual practice to use a slip feeding device to disable the check feeding mechanism when a slip is inserted in the machine. However in the machine of the instant invention which is arranged to make a varying number of imprints upon the slip and check, for example, one or two imprints upon the slip, and one imprint upon the check, it was necessary to provide means in addition to the slip feeding device to control the impression mechanism.

Therefore it is broadly an object of this invention to provide means to control the impression mechanism of accounting machines and cash registers.

Another object is to provide positionable means to control the check feeding mechanism, the printing hammer, and a closure guarding the aperture through which the insertable slips are presented to the impression mechanism.

Another object is to provide means controlled by an insertable slip to govern the printing hammer.

Other objects of the present invention are: to supply means to feed the slip; to provide means to return the positionable means to a particular position each machine operation; to provide means to move the positionable means from a particular position to a neutral, or ineffective, position in order to control the impression mechanism in certain types of operations, and to provide means controlled by the positionable means to print a symbol characteristic of the type of operation, slip or check, being performed.

With these and incidental objects in view, the invention includes certain novel features of construction and combination of parts, the essential elements of which are set forth in appended claims and a preferred form or embodiment of which is hereinafter described with reference to the drawings which accompany and form a part of this specification.

Of said drawings:

Fig. 1 is a side elevation as observed from the left of the machine showing the impression

mechanism and the positionable member for controlling same.

Fig. 2 is a side elevation of a portion of the mechanism for controlling the feeding of the check material. 5

Fig. 3 is a detail view of the mechanism for controlling the parts shown in Fig. 2.

Fig. 4 illustrates the slip feeding mechanism.

Fig. 5 is a side elevation as observed from the left of the machine showing the impression 10 mechanism and the slip feeler mechanism for controlling same.

General description

The printing mechanism of the machine of the instant invention, consisting of a single hammer and a single line of type wheels, is arranged to print either upon an issuing check or upon an insertable slip. With this type of impression mechanism it is obviously impossible to make imprints upon both the check and the slip at the same time. Consequently it is necessary to incorporate controlling mechanism in the machine to prevent the insertion of a slip when it is desired to issue a check or receipt, and to prevent the issuing of a check when it is desired to print upon a receipt or slip. 15 20 25

The impression mechanism of the instant machine is arranged to make a varying number of imprints upon the slip and check. For example, 30 either one or two imprints may be made upon the insertable slip during one machine operation, or one imprint may be made upon the issuing check in one machine operation. This varying of the number of imprints upon the insertable slip complicates the control of the impression mechanism to a marked degree and necessitated the development of the novel mechanism which is the subject of this invention. 35

This novel mechanism includes a settable member movable to three positions, an intermediate or neutral position, an upper or check printing position, and a lower or slip printing position. The settable member remains normally in check printing position and is automatically returned from 45 any other position to this position near the end of each machine operation. The printing hammer of the instant machine is arranged to make two printing strokes each machine operation. When the settable member is in neutral position 50 the check feeding mechanism is disabled, the impression hammer is blocked against printing movement and an obstruction is moved to effective position to prevent insertion of a slip in the slip chute. Also when the settable member 55

is in neutral position the feeler mechanism that controls the hammer during slip printing operations is retained ineffective.

When the settable member is in its upper, or 5 check printing, position the obstruction continues to bar the entrance to the slip chute. However the hammer disabling mechanism is rendered ineffective. After the hammer performs one printing movement the settable member is automatically 10 moved to neutral position, to disable the hammer so that only one impression will be made upon the issuing check. Also when the settable member is in check printing position the check feeding mechanism becomes effective to issue 15 checks with a single impression thereon.

Moving the settable member to its lower or slip printing position opens the slip chute, moves the hammer disabling mechanism to ineffective position, disables the check feeding mechanism and 20 renders the slip feeding mechanism effective. As previously stated, one or two impressions may be made upon the slip. This is governed by means of an adjustable stop located in the slip chute in cooperation with the slip feeler mechanism. Prior 25 to each printing movement of the hammer the feeler mechanism feels for the slip and if the slip obstructs upward movement of said feeler mechanism the hammer is free to make a printing stroke. In case the slip is not properly inserted in the 30 chute or is moved beyond the feeler mechanism by means of the slip feeding mechanism upward movement of the slip feeler is not obstructed and consequently the hammer is disabled for printing movement. After the first impression is made 35 upon the slip it is fed forwardly by the slip feeding mechanism. If the slip stop has been adjusted for two impressions the slip will continue to block upward movement of the slip feeler thereby causing another impression to be made upon said slip. When the stop is adjusted for a single impression 40 the feeding of the slip after the first impression moves the end thereof beyond the slip feeler to block the second printing movement of the hammer.

45 The mechanisms outlined in a general way above will now be described in detail.

Detailed description

Inasmuch as the mechanism of the instant invention may be applied to most any accounting machine or cash register, it is thought unnecessary to explain this mechanism in connection with any particular type of machine. Therefore only the register mechanism having a direct bearing 55 upon the instant invention will be described in connection therewith.

Impression mechanism

Directing attention to Figs. 1 and 5, loose on a 60 shaft 30, supported by the printer frame, is an impression hammer 31, with an impression block or platen 32, which cooperates with a plurality of type wheels 33 loose on a shaft 34, likewise supported by the printer frame. The type wheels 33 65 are differentially positioned by means of depressible amount keys, or in some machines by means of settable levers representing the different denominations of the machine. Also loose on the shaft 30 is a hammer operating cam 35, integral 70 with a gear 36 which is connected to the machine operating mechanism and makes one revolution in a clockwise direction for each operation of the machine. The periphery of the cam 35 cooperates with a roller 37 on a plate 38 rotatably supported 75 by a stud 39 in the left frame of the machine. A

comparatively strong spring 40 urges the plate 38 counterclockwise to maintain the roller 37 normally in contact with the periphery of the cam 35. A spring 41 is stretched between the plate 38 and the impression hammer 31 to normally maintain said hammer in contact with a stud 42 carried by said plate 38.

When the machine is at rest an eccentric portion 351 of the cam 35 maintains the impression hammer away from the printing type in the position shown in Fig. 1. As the cam 35 rotates the contour thereof allows the hammer 31 to move slowly toward the type wheels, however this movement is not sufficient to cause an impression.

Next one of two identical nodes 43 of the cam 35 15 engages the roller 37 and rocks the plate 38 and hammer 31 full distance clockwise away from the type wheels. As the roller 37 rides off the abrupt edge of the node 43 the spring 40 imparts sufficient impetus to the plate 38 and hammer 31 20 to cause the platen 32 to force the record material and its superimposed ribbon into contact with the type wheels 33 to make an imprint on said record material. Impression movement of the plate 38 is stopped just before the platen 32 contacts the 25 type wheels the momentum of the hammer 31 being sufficient to complete the impression. After impression, the spring 41 prevents rebound of the impression hammer to eliminate the possibility of blurring the imprint. The second node 43 of the 30 cam 35 causes a second impression to be made upon the record material in exactly the same manner as explained above.

Impression control lever

An impression control lever 44 (Fig. 1) pivoted on a stud 45 in the left machine frame has three positions a check printing position, a neutral or non-printing position and a slip printing position. These positions are governed by means of three 40 V-shaped notches 46 in said lever cooperating with the rounded nose of a pawl 47 pivoted at 48 to the left machine frame. Connected to the upper end of the pawl 47 is a link 49 with a slot which embraces a fixed stud 50. A spring 51, tensioned 45 between the stud 50 and the pawl 47 urges said pawl counterclockwise into communication with the notches in the lever 44. The lower end of the link 49 cooperates with a stud 52 in a cam 53 which receives one clockwise rotation each machine operation. Near the end of machine operation the stud 52 moves the link 49 forwardly to rock the pawl 47 clockwise to disengage its rounded nose from the notches in the impression control lever 44. A spring 54 then returns the lever 55 44 counterclockwise from either the neutral or slip printing position to the check printing position which is the normal position of said lever.

The lever 44 has therein a slot 55 adapted to receive a stud 56 in a lever 57 loose on a fixed 60 trunnion 58 (see also Fig. 5). A downward extension of the lever 57 has therein a stud 59 which extends within a slot in an arm 60 secured on a shaft 61 journaled in the printer frame. Secured on the shaft 61 is a shutter 62 an upward extension of which is adapted to be moved at certain times through an aperture in the lower plate of a slip chute 63. Also secured on the shaft 61 is an arm 64 with a right-angled extension 65 which engages the upper surface 70 of an extension 66 of a slip feeler 67 mounted for vertical movement on the printer frame by means of slots therein in cooperation with a pair of studs 68 secured in the printer frame. The upper end of the slip feeler 67 is adapted to 75

move through an opening in the lower plate of the slip chute 63 and communicates with the slip opening in said chute in a manner presently to be described.

5 As shown in Fig. 5, the lever 44 is in its upper or check printing position, in which position the lever 57 in cooperation with the arm 60 positions the shaft 61 so that the shutter 62 obstructs the opening in the slip chute 63 thereby preventing insertion of slips. At this time the arm 64 prevents upward movement of the slip feeler 67 which movement disables the printing stroke of the hammer 31 in a manner later to be described. Moving the lever 44 to the neutral position (Fig. 5) by means of the slot 55 rocks the lever 57 counterclockwise for a purpose presently to be described. However, due to the contour of the slot in the arm 60 this movement is not transmitted to the shaft 61. Consequently 10 the shutter 62 and the arm 64 remain in their effective position as here shown.

15 After the impression hammer 31 has completed one printing stroke in a check printing operation the lever 44 is automatically moved to neutral position to block the second printing movement of said hammer to prevent two impressions being made upon the issuing check. The mechanism for accomplishing this result will now be described.

20 By studying Fig. 1 it will be observed that the stud 52 in the cam 53 cooperates with an arcuate surface 69 of a pitman 70 slidably supported by means of a slot through which extends the stud 50 and another slot embracing a fixed stud 35 71. The forward surface 72 of an upward extension of the pitman 70 cooperates with a stud 73 in the lever 44. A link 74 connects the lever 44 to a bell crank 75 loose on a stationary stud 76 and resiliently connected by a spring 77 to a hammer disabling pawl 78 also loose on the stud 76. A notch 79 in the lower end of the pawl 78 cooperates with a projection 80 of the hammer 31.

25 When the lever 44 is moved to check printing position by the spring 54, the link 74 rocks the bell crank 75 clockwise to move the notch 79 of the pawl 78 out of the path of the projection 80 thereby permitting impression movement of the hammer 31. Immediately after the first impression stroke of the hammer, the stud 52 30 engages the surface 69 to move the pitman 70 forwardly, causing said pitman, in cooperation with the stud 73 to rotate the lever 44 clockwise from the check printing position to neutral position. This clockwise movement of lever 44 cams pawl 47 out of the notch 46 for the slip position and permits the pawl 47 to engage the intermediate notch shown in Fig. 1, in the same manner as when the lever 44 is moved by hand. 35 40 This rocks the bell crank 75 counterclockwise to cause the right edge (Fig. 1) of the pawl 78 to resiliently engage the projection 80, which it will be understood is now above the notch 79 due to the contour of the cam 35. Consequently 45 when the cam 35 rocks the hammer 31 clockwise for a second impression stroke the notch 79 of the pawl 78 bypasses the projection 80 to block the second impression movement of the hammer 31. Near the end of machine operation the lever 44 is automatically returned to check printing position in the manner explained above. It is therefore obvious that the mechanism just described prevents more than one impression being made upon the issuing check.

Control of check feeding mechanism

5 Super-imposed feeding rolls 83 and 84 (Fig. 2) advance the check web to the impression mechanism. When the impression control lever 44 (Fig. 1) is in check printing position, mechanism becomes effective to move the lower feed roller 84 toward the upper roller 83 thereby gripping the check web between said rollers. The rollers are then rotated at the proper time to feed the check material to the impression mechanism. A pitman 85 (Fig. 3), connected to the lever 57, is bifurcated to embrace a shaft 86 journaled in the bent-over ears of a bracket 87 secured to a machine cross-frame 88. Pivoted at 89, to the pitman 85, is a lever 90 with a roller 91, which cooperates with the periphery of a plate cam 92, fast on a shaft 93, journaled in the main machine frames. The lever 90 has a stud 94 coacting with an arm 95 secured on the shaft 86. Also secured on the shaft 86 (Fig. 2) is an arm 96 bifurcated to receive a stud 97 in a bar 98 mounted for vertical reciprocating movement by means of slots therein cooperating with fixed studs 99 and 100.

10 A plate 101 is slidably attached to the bar 98 by means of vertical slots in said plate in cooperation with a pair of studs 102 carried by said bar 98. The plate 101 has a stud 103 coacting with the top surface of a latch 104 pivoted to a slide 105 mounted for horizontal reciprocating movement by means of a slot in said slide through which extends the stud 100 and by means of the bifurcated rearwardly disposed end of said slide in cooperation with a shaft 106 journaled in the main machine frames. The slide 105 carries a roller 107 which extends within a cam groove 108 in a cam 109 secured on the shaft 106. The latch 104 has a notch adapted to latch over a stud 110 extending through a clearance opening in the slide 105 and secured in a segment 111 rotatably supported by a shaft 112 which also supports the upper feed roll 83. The segment 111 meshes with a pinion 113 secured to an eccentric 114 in such a manner that the axis of said pinion coincides with the axis of a shaft 115 which loosely supports the eccentric 114. The shafts 112 and 115 are journaled in the printer frame. The lower feed roll 84 is turnably mounted upon the eccentric 114. In Fig. 2 the roll 84 is partly broken away to more clearly show the parts 111 and 113. A spring 116 is tensioned to urge the latch 104 clockwise to normally maintain said latch out of engagement with the stud 110 and to normally maintain the plate 101 and the bar 98 in their upward positions as shown in Fig. 2. A stud 117 in the latch 104 cooperating with the lower edge of the slide 105 controls the extent of the clockwise movement of said latch.

15 Moving the impression control lever 44 (Fig. 1) to check printing position rocks the lever 57 (Fig. 3) clockwise to position the pitman 85 so that the roller 91 is in the path of the cam 92. Counterclockwise rotation of the cam 92 during machine operation rocks the lever 90 counterclockwise which by means of the stud 94 rocks the arm 95, the shaft 86 (see also Fig. 2) and the arm 96 clockwise to move the bar 98 and the plate 101 downwardly to rock the latch 104 counterclockwise to engage the notch therein with the stud 110 in the segment 111.

20 Counterclockwise movement of the cam 109 causes the raceway 108 in cooperation with the roller 107 to move the slide 105 rearwardly to impart counterclockwise movement to the seg- 25

ment 111. The segment 111 rotates the pinion 113 and the eccentric 114 clockwise to cause the roller 84 to contact the check material against the upper roller 83. Subsequent rotation of the rollers 83 and 84 feeds the proper amount of the check material to the impression mechanism.

Moving the impression control lever 44 away from check printing position to either neutral or slip printing position rocks the lever 57 (Fig. 3) 10 counterclockwise to move the roller 91 out of the path of the cam 92. The latch 104 therefore remains disengaged from the stud 110 and the slide 105 works idly back and forth without imparting any movement to the segment 111, therefore 15 by preventing feeding of the check material.

Slip feeler mechanism

By observing Figs. 4 and 5 it will be recalled that moving the lever 44 to slip printing position 20 imparts maximum counterclockwise movement to the lever 57 to rock the shaft 61 and the arm 64 clockwise to move the projection 65 out of the path of the slip feeler 67. It is therefore 25 obvious that the only time the slip feeler is free to function is when the lever 44 is in slip printing position. In slip printing operations prior to each printing movement of the hammer 31, the feeler 67 feels for a slip 82. If the feeler contacts the slip the printing mechanism is free 30 to function and in case the feeler fails to contact the slip, printing movement of the hammer 31 is blocked.

The feeler 67 has a horizontal slot which embraces a stud 118 in an arm 119 secured on a 35 shaft 120 journaled in the printer frame. Also secured on the shaft 120 is an arm 121 flexibly connected by spring 122 to a pawl 123 loose on said shaft 120. The pawl 123 has a step cut 124 adapted to cooperate with the top surface 125 40 of a bent portion of the impression hammer 31. Also secured on the shaft 120 is an arm 126 pivotally connected to the forwardly disposed arm of a bell crank 127 loose on a fixed pivot 128. A downward extension of the bell crank 45 127 carries a stud 129 which extends within a slot in a link 130 connected to an arm 131 secured on a shaft 132 journaled in the printer frame. Secured on the shaft 132 is another arm 133 with a stud 134 which cooperates with 50 the periphery of a cam 135 secured on the shaft 106.

When the machine is at rest one of two identical nodes 136 of the cam 135 by means of the chain of mechanism just described, retains the 55 feeler 67 in its downward position as here shown. It will be recalled that moving the lever 44 to slip printing position rocks the shutter 62 clockwise to remove the obstruction 62 from the opening in the slip chute, through which the insertable slip 82 is presented to the printing mechanism. The slip may now be inserted in the 60 chute and located in relation to the printing mechanism by means of an adjustable stop 137 (Fig. 4) interposed between the upper and lower 65 plates of the slip chute 63. At the beginning of machine operation counterclockwise movement of the cam 135 immediately moves the node 136 out of the path of the stud 134 thereby releasing the arm 126 and the shaft 120 to the action of a 70 spring 138 which urges said shaft in a counterclockwise direction. The shaft 120 by means of the arm 119 urges the feeler 67 upwardly into the opening of the slip chute and by means of the arm 121 tends to move the step 124 of the 75 pawl 123 over the surface 125 to block counter-

clockwise printing movement of the hammer 31. However the inserted slip 82 blocks upward movement of the feeler 67 consequently the step 124 is retained out of the path of the surface 125 and the printing hammer 31 is free to make 5 its printing stroke.

When no slip is in the machine to block movement of the feeler 67, the shaft 120 and arm 123 continue to rock counter-clockwise until the shoulder 124 is over the flange 125 of the printing hammer 31, and then no impression is made. 10

Slip feeding mechanism

After the first imprint has been made upon the slip the mechanism shown in Fig. 4 line-spaces the slip so that the second imprinting will take place, for example, on a detachable coupon or portion of the slip. This mechanism consists of a cam 140 secured on a shaft 141 journaled in the printer frame, said cam adapted 20 to cooperate with a roller 142 carried by a lever 143 journaled on a stud 144 in the printer frame. The lever 143 carries a stud 145 upon which is pivoted a segment 146 carrying a roller 147 which cooperates with an arm 148 secured on a shaft 25 149 journaled in the printer frame. The segment 146 is operatively connected by a pinion 151 loose on a stud in the arm 143 to a pinion 152 secured to a knurled feed roll 153 rotatably mounted on a stud in the lever 143. An aperture 30 in the lower plate of the slip chute permits the feed roller 153 to coast with a knurled upper feed roll 154 loose on a trunnion supported by an upward extension of the slip chute 63, said roller 35 extending through an aperture in the top plate of the slip chute into the slip opening therein.

At the beginning of machine operation movement of the cam 140 allows a spring 156 to rock the lever 143 counterclockwise to cause the roller 153 to move the slip against the upper roller 40 154. After the first impression has been made the arm 148 is rocked first in a counterclockwise direction and in cooperation with the roller 147 rocks the segment 146 clockwise, which by means of the intermediate pinion 151 rotates the lower 45 feed roll 153 clockwise to line-space the slip. Immediately after the second impression is completed the cam 140 returns the lever 143 clockwise to its normal position after which the arm 148 is returned clockwise to normal position. A spring 157 returns the segment 146 counterclockwise to normal position, which position is determined by means of a stud 158 in the lever 143 cooperating with the edge of said segment. 50

In case it is desired to make only one imprint 55 upon the slip, moving the stop 137 (Fig. 4) forwardly locates the slip so that line-spacing thereof after first impression moves the rearwardly disposed edge of said slip beyond the feeler 67 (see also Fig. 5). Consequently when the cam 135 allows the feeler to make its second upward movement the slip does not obstruct such movement and the pawl 123 engages the surface 125 and blocks impression stroke of the hammer 31 in the manner explained above. Oscillating movement of the shaft 149 also operates a knife 150 (Fig. 4) to sever the checks. 60

Symbol printing mechanism

Referring to Fig. 1, when the impression control lever 44 is in check printing position, a symbol segment 159 is positioned so that the letter "C" will be printed on a detail strip web 160. Moving the lever 44 to the slip printing position 70 positions the segment 159 so that the letter "S" 75

which is symbolic of a slip printing operation will be printed on the detail strip. When the lever is in neutral position a blank portion of the segment 159 is opposite the impression mechanism for the detail strip. Consequently at this time no imprint will be made thereon. The symbol printing mechanism will now be described in detail.

There are duplicate sets of characters on each 10 of the type wheels 33, one set of which prints upon either the check or insertable slip and the other set of which is adapted to print upon the detail strip 160. The web of the detail strip 160 is wound around various rollers and an impression 15 roller 161 supported by a rockable frame. During each machine operation the rockable frame causes the impression roller 161 to move the detail strip 160 into contact with an inking ribbon (not shown) and the type wheels 33, to 20 make a legible record of each transaction upon the detail strip.

The segment 159 is loose on the shaft 34 and is urged clockwise by a torsion spring 162 to normally maintain a notch in an extension 25 thereof in engagement with a stud 163 in an arm 164 fast on a shaft 165 supported in the printer frame. Also secured on the shaft 165 is an arm 166 with a cam slot 167 adapted to receive a stud 168 in the link 74.

When the segment 159 is in neutral position as here shown, an undercut portion thereof is opposite the impression roll 161. Consequently upon machine operation no characteristic imprint is made upon the detail strip 160. Moving 30 the lever 44 to slip printing position rocks the arm 166, the shaft 165 and the arm 164 clockwise, which in turn rocks the segment 159 counterclockwise to locate the letter "C" engraved thereon opposite the impression roll 161. It is, 35 therefore, obvious that in check printing operations the letter "C" is printed upon the detail strip 160 to record the type of operation being performed. The pitman 70 returns the lever 44 from check position to neutral position while the 40 impression roll 161 still impinges the detail strip against the printing segment 159. In order to prevent a blurring of the imprint the notch in the downward extension of the segment 159 allows said segment to remain stationary while 45 the arms 166 and 164 and the shaft 165 are being returned counterclockwise. After the impression is complete the spring 162 returns the segment 159 clockwise to reengage the notch therein with the stud 163.

Moving the lever 44 to slip printing position 50 causes the link 74 and the stud 168 to rock the arm 166 counterclockwise, due to the configuration of the slot 167 in said arm, to position the segment 159 so that the letter "S", symbolic of 55 a slip operation, is opposite the impression roll 161. Subsequent operation of the machine causes the letter "S" to be imprinted upon the detail strip to record the slip printing operation.

The automatic return of the lever 44 to check 60 printing position, as explained earlier herein, by means of the link 49, in cooperation with the stud 52 does not occur until after the second impression upon the detail strip is completed, thereby 65 eliminating the danger of the impression interfering with the automatic return of the lever and likewise eliminating the danger of the automatic return of the lever blurring the impression.

It is felt that a clear understanding of the 70 operation of the machine will have been obtained 75 from the foregoing description, and for this rea-

son no explanation of operation is included herein.

While the form of mechanism herein shown and described is admirably adapted to fulfill the objects primarily stated, it is to be understood that it is not intended to confine the invention to the one form or embodiment herein disclosed, for it is susceptible of embodiment in various forms, all coming within the scope of the claims which follow.

What is claimed is:

1. In a machine of the class described having a plurality of type carriers, the combination of impression means; means to impart two working movements to the impression means each machine operation; positionable means adapted to be adjusted to a plurality of positions, to control the impression means; means to retain the positionable means in any of its positions; means to move the positionable means from one position to another to prevent the second movement of the impression means; means to operate the moving means and to render the retaining means ineffective; and resilient means to return the positionable means to its one position.

2. In a machine of the class described, the combination of means to make impressions on record material; means including feed rollers to advance the record material to a printing point; means to move the rollers together to grip the record material there-between; means to operate the moving means; manipulative means; and means controlled by the manipulative means to couple the operating means to the moving means.

3. In a machine of the class described, the combination of means to make impressions on record material; feed rollers to advance the record material to the impression means; means to move the rollers together to grip the record material there-between; means to operate the moving means; an element on the operating means to connect said moving means and the operating means; means to shift the element into connecting position; and manipulative means to render the last named means effective.

4. In a machine of the class described, the combination of means to make imprints on record material; means to advance the record material to the imprinting means; means to shift an element of the advancing means whereby the advancing means grips the record material; means to operate the shifting means; means, including a reciprocating element, to connect the operating means to the shifting means; means to drive the reciprocating element; and manipulative means to render the driving means effective.

5. In a machine of the class described, the combination of means to make imprints on record material, means to advance record material to the imprinting means; means to shift a portion of the advancing means into position to grip the record material to enable feeding thereof; means to operate the shifting means; means to connect the operating means to the shifting means; positionable means; and means, intermediate the positionable means and the connecting means, controlled by said positionable means, to render the connecting means effective.

6. In a machine of the class described, having a plurality of type carriers, the combination of means to impress record material against the type carriers; a chute to guide the record material to the type carriers; a closure for the chute; an element to feel for the record material means controlled by the feeler to disable the imprinting

- means when said record material is not in the path of the feeler; actuating means to intermittently actuate the feeler during a machine operation; and positionable means to render the element ineffective irrespective of the actuating means and to simultaneously shut the closure.
7. In a machine of the class described having a plurality of type carriers, the combination of means to impress record material against the type carriers; a receptacle for the record material; a closure for the receptacle; means adapted to feel for the record material; means controlled by the feeling means to disable the impression means when no slip is in the path of the feeler; means to render the feeling and disabling means operative prior to impression; and manipulative means to control the feeling means irrespective of the rendering means and to simultaneously control the closure.
8. In a machine of the class described, the combination of means to make imprints on record material; feed rollers to advance the record material to a printing point; means to move the rollers together to grip the record material there-between; means to operate the moving means; a positionable member; and means whereby the positionable member controls the operating means and the imprinting means.
9. In a machine of the class described having a plurality of type carriers, the combination of means to impress record material against the type carriers; feed rollers to advance the record material to the type carriers and the impressing means; means to move the feed rollers together to grip the record material there-between; means to operate the moving means; means to connect the operating means to the moving means; and a positionable member to control the connecting means and the impressing means.
10. In a machine of the class described having a plurality of type carriers, the combination of means to impress record material against the type carriers; feed rollers to advance the record material to the type carriers and the impressing means; means to move the feed rollers together to grip the record material there-between; means to operate the moving means; means connecting the operating means to the moving means; means to impart two working movements to the impressing means each machine operation; positionable means to control the moving means and the impressing means; and means to move the positionable means from one position to another to prevent the second movement of the impressing means and to render the operating means ineffective.
11. In a machine of the class described, the

combination of means to print on insertable record material; a receptacle for the record material; a closure for the receptacle; record material feeling means; means to normally latch the feeling means against operation; means, controlled by the feeling means during an operation of the machine, to disable the printing means when the record material is not in the path of the feeling means; and manipulative means, to release the feeling means and to open the closure.

12. In a machine of the class described having a plurality of type carriers, the combination of means to impress record material against the type carriers; a chute to guide the record material to the type carriers; a record material feeler; means adjusted under control of the feeler to disable the impressing means when the record material is not in the path of the feeler; means to release the disabling means prior to an impression; and manipulative means, superseding the releasing means, to retain the disabling means in an ineffective position irrespective of the releasing means.

13. In a machine of the class described having a plurality of type carriers, impression means, and means to impart two working strokes to the impression means during each machine operation, the combination of a manipulative means shiftable from a normal position to a plurality of positions to control the operation of the impression means, means for retaining the manipulative means in shifted positions, means operable to shift the manipulative means from one position to another to prevent a second working stroke of the impression means, means to return the manipulative means to its normal position, means to release the retaining means for the manipulative means whereby the restoring means may become effective near the end of a machine operation, and means to actuate the shifting means and the releasing means in proper timed relation during a machine operation.

14. In a machine of the class described, the combination of means to make printed records on record material, means to advance the record material to the printing means, enabling means to cause the advancing means to grip the record material to enable the feeding thereof, means to operate the enabling means, means to connect the operating means to the enabling means, a cam, means, including a member operable by said cam, to render the connecting means effective, and manipulative means to move said member into or out of operative relation with the cam.
